UNITED STATES PATENT OFFICE

STEPHEN BATTNER, OF NORTH TONAWANDA, NEW YORK, ASSIGNOR TO THE RUDOLPH WURLITZER MANUFACTURING COMPANY, OF NORTH TONAWANDA, NEW YORK, A CORPORATION OF NEW YORK

EXPRESSION DEVICE FOR MUSICAL INSTRUMENTS

Application filed July 10, 1929. Serial No. 377,287.

This invention relates to improvements in expression devices for automatic musical instruments, particularly player or reproducing pianos.

One of its objects is the provision of an expression device which is simple, compact and durable in construction, which is reliable and efficient in operation, and whose parts are so organized and arranged as to accurately reproduce fine grades of expression or step changes in playing intensity.

Other features of the invention reside in the novel construction and arrangement of parts hereinafter described and particularly pointed out in the appended claims.

In the accompanying drawings:

Figure 1 is a sectional side elevation of an expression device embodying my improvements. Figure 2 is a front end view thereof. Figure 3 is an end view of the clutch control mechanism of my device.

Similar characters of reference indicate corresponding parts throughout the several views.

In the preferred embodiment of the invention shown in the drawings, 10 indicates a wind chest of any well known construction having a passage 11 for connection with a main source of power or suction (not shown), such as a bellows for operating the playing pneumatics of the instrument. Interposed in this passage is a partition 12 having a valve-controlled port 13. The passage 11 at one side of the partition may be termed the high or unregulated exhaust chest and the passage 14 at the other side of said partition may be termed the regulated exhaust chest, which communicates, as is well understood in the art, with the action chest of the player action operated selectively from the usual tracker board. Applied to the port 13 is a regulator valve 15 which governs the flow of air from the action chest passage 14 to the source of supply passage 11.

The means for controlling the valve 15 to obtain the various grades of expression desired are preferably constructed as follows:

The numeral 16 indicates a regulator pneumatic or governor which communicates with the regulated exhaust passage 14 through a

port 17 and which has a spring 18 connected to its movable board to yieldingly resist its collapse, said pneumatic tending to close the valve 15. Disposed in opposing relation to the regulator pneumatic is a main expression pneumatic 19 and located between them is a rock lever 20 pivoted at 21 to swing in the direction of movement of the movable boards of such pneumatics. Pivoted at 22 to the free end of this rock lever to swing laterally thereof is a centralizing rocker arm 23, one end of which is connected by a link 24 with the movable board of the regulator pneumatic 16, while the other end thereof is connected by a similar link 25 with the corresponding board of the expression pneumatic 19. The regulator valve 15 is suspended from the rock lever by a rod or stem 26 secured at its lower end to the valve and extending freely at its upper end through an opening in the lever. Above the lever this rod has a nut 28 and interposed between the latter and the lever is a spring 29 which yieldingly sustains the valve 15, the tension of such spring being stronger than that of the suction or full atmospheric pressure. The connection of the regulator and expression pneumatics with the actuating valve lever 20 results in the opening of the valve 15 upon the collapse of the expression pneumatic and in the closing of the valve upon the collapse of the regulator pneumatic; in each case the rocker arm 23 constitutes a lever between the links 24, 25 and the points of attachment of the latter with the rocker arm constitute pivots about which said arm turns in transmitting the movements of the pneumatics to the valve-actuating lever.

A series of auxiliary expression pneumatics 30 for the purpose of obtaining quick accenting effects are provided which are adapted to control the valve 15 independent of the main expression pneumatic 19. For this purpose a rock shaft 31 is provided which is arranged substantially parallel to the rock lever 20 and which is journaled at its ends in suitable bearings 32. Projecting radially from the shaft are a series of arms 33 connected at their outer ends with the movable boards of the corresponding auxiliary ex-

pression pneumatics 30 through the medium of springs 34, which are capable of being readily adjusted to the desired tension. Another radial arm 35 is secured to the rock 5 shaft and connected therewith is the upper end of the valve stem 26 to which an adjusting nut 26^a is applied for engagement with the top side of said arm 35, so that when one or another of the auxiliary expression pneumatics is collapsed the shaft 31 is accordingly 10 rocked downwardly to lower or open the valve 15, the latter being thus controlled in this instance independently of the pneumatics 16 and 19. It is also to be noted that 15 the connection between the regulator pneumatic 16 and the main expression pneumatic 19 is such that the position of the former is not in any way influenced by the latter, but only by the regulator valve 15.

20 The main and auxiliary expression pneumatics may be controlled automatically from the tracker board of the instrument in any approved manner.

25 The expression pneumatic 19 is provided with automatic means for holding its movable board in different positions so as to obtain finer grades of expression in combination with the auxiliary pneumatics 30. For this purpose a rack bar 36 is provided which 30 is pivoted at 37 to the movable board of the pneumatic 19 while its other end meshes with a pinion 38 mounted on a spindle 39 secured to a bracket 40 and carrying a clutch-disk 41, the latter and its pinion being free to revolve 35 on said spindle. The rack bar is held in engagement with the pinion by a roller 42 applied to the bracket and bearing on the cushioned face of the rack bar, as seen in Figure 1. Movable into and out of engagement 40 with the disk 41 is a companion clutch-disk 43 splined on the spindle and constantly urged into frictional engagement therewith by a spring 44. A lever 45 engaging a grooved collar 46 on the movable clutch-disk is pro- 45 vided for shifting the same out of engagement with its companion disk, said lever being pneumatically controlled from the tracker by pneumatics 47, 48 disposed side by side. The pneumatic 47 operates in conjunction 50 with the expression pneumatic 19 to release the clutch disks 41, 43 when exhausting the latter pneumatic to increase the tension, and the other pneumatic 48 operates independently of said pneumatic 19 to release the 55 clutch and permit the same to vary the expression of the selection being rendered. Leading from the pneumatics 19, 47 are conduits 49, 50 which are joined to a common conduit 51 connected to a duct in the tracker 60 (not shown), while the pneumatic 48 is connected by a conduit 52 with another duct in the tracker. Secured to the movable board of the pneumatic 47 is a cleat 53 which over- 65 lies the corresponding board of the companion pneumatic 48, as that whenever said

first-named pneumatic is collapsed by the uncovering of the respective tracker-duct, such companion pneumatic is likewise collapsed. The movable board of the latter, however, is not attached to the cleat so that it is capable of being collapsed independently of the pneumatic 47 for the purpose presently to be described. The clutch lever 45 is connected by a link 54 with the pneumatic 48, so that whenever the latter is compelled to be simultaneously collapsed with the companion pneumatic 47, or is caused to be independently collapsed, the clutch disks 41, 43 are released, permitting the expression pneumatic 19 to be deflated or inflated to produce the desired step by step grades of expression. In other words, the pneumatic 47 releases the clutch to permit the deflation of the expression pneumatic 19 and the companion pneumatic 48 releases the clutch to enable the expression pneumatic to return to its inflated position. The length of the expression-controlling holes in the note sheet determines the degree of deflation or inflation of the pneumatic 19 and the moment such openings pass 60 out of register with their corresponding tracker ducts, the spring 44 promptly engages the clutch elements, arresting said pneumatic and maintaining it in any intermediate 65 position until released to produce a different grade of expression.

Briefly stated, the operation of this expression device is as follows:—

When the instrument is started, a partial 100 vacuum is created in the wind chest 10 to operate the playing pneumatics, such vacuum tending to collapse the regulator pneumatic 16 against the resistance offered by its spring 18. As the regulator pneumatic collapses, it 105 rocks the lever 20 in a direction to partially close the regulating valve 15. If the volume of regulated air in the wind chest is small, the regulator pneumatic will collapse more and tend to more fully close the valve to cut off the main supply, while should the volume 110 increase, the regulator pneumatic will be inflated proportionately and the valve will be opened wider.

When a gradual expression is desired, such as crescendo, the main expression pneumatic 19 is brought into operation in the customary way, which will result in its being deflated more or less and thus cause the regulating valve 15, through the connections 20, 23, 24 and 25, to be opened wider and permit a larger volume of high tension partial vacuum to be admitted to the regulator pneumatic which in turn collapses a further degree. It will be understood that the governor pneumatic will be working under high tension and will constantly tend, through the rocker arm 23 and rock lever 20, to close the valve. Should the volume be greater at times, the governor pneumatic will open the valve wider to compensate for such larger volume.

When a quick or accentuating expression is desired, the auxiliary expression pneumatics 30 are brought into play which act when deflated, to open the valve 15 independently of the main expression pneumatic by rocking the shaft 31 accordingly and forcing the valve stem 26 downwardly against the resistance of the spring 29. When the expression pneumatic or pneumatics 30 are again inflated, the spring returns the valve to its initial position.

The provision of the clutch mechanism makes it possible to automatically maintain the expression pneumatic in any position for producing desired playing intensities of varying duration.

I claim as my invention:—

1. An expression device for automatic musical instruments, comprising a regulating pneumatic, a regulating valve interposed between the source of power and the playing action of the instrument, an expression pneumatic arranged in opposing relation to said regulating pneumatic, an actuating lever for said valve operatively connected to said regulating pneumatic and said expression pneumatic, the deflation of the regulating pneumatic tending to close the valve and the deflation of the expression pneumatic tending to open the valve, and automatic means for releasably holding said expression pneumatic in any intermediate position.

2. An expression device for automatic musical instruments, comprising a regulating pneumatic, a regulating valve interposed between the source of power and the playing action of the instrument, an expression pneumatic arranged in opposing relation to said regulating pneumatic, an actuating member for said valve operatively connected to said regulating pneumatic and said expression pneumatic, means for holding the latter in different intermediate positions, and automatic means for releasing said holding means.

3. An expression device for automatic musical instruments, comprising a regulating pneumatic, a regulating valve interposed between the source of power and the playing action of the instrument, an expression pneumatic arranged in opposing relation to said regulating pneumatic, an actuating lever for said valve fulcrumed at one end to swing in the plane of movement of the movable boards of said pneumatics, said valve having a stem suspended from said lever intermediate its ends, and connections between the free end of said lever and the expression and regulating pneumatics.

4. An expression device for automatic musical instruments, comprising a regulating pneumatic, a regulating valve interposed between the source of power and the playing action of the instrument, an expression pneumatic arranged in opposing relation to said regulating pneumatic, an actuating lever for

said valve fulcrumed at one end to swing in the plane of movement of the movable boards of said pneumatics, said valve having a stem suspended from said lever intermediate its ends, connections between the free end of said lever and the expression and regulating pneumatics, and clutch means for holding said expression pneumatic in different intermediate positions.

5. An expression device for automatic musical instruments, comprising a regulating pneumatic, a regulating valve interposed between the source of power and the playing action of the instrument, an expression pneumatic arranged in opposing relation to said regulating pneumatic, an actuating lever for said valve fulcrumed at one end to swing in the plane of movement of the movable boards of said pneumatics, said valve having a stem suspended from said lever intermediate its ends, a spring applied to the valve stem above said lever and bearing thereon, and connections between the free end of said lever and the expression and regulating pneumatics.

6. An expression device for automatic musical instruments, comprising a regulating pneumatic, a regulating valve interposed between the source of power and the playing action of the instrument, an expression pneumatic arranged in opposing relation to said regulating pneumatic, an actuating member for said valve operatively connected to said regulating pneumatic and said expression pneumatic, pneumatically operated clutch means for releasing said expression pneumatic, and an auxiliary expression pneumatic operatively connected to said valve for controlling it independently of said main expression pneumatic and said actuating member.

7. An expression device for automatic musical instruments, comprising a regulating pneumatic, a regulating valve interposed between the source of power and the playing action of the instrument, an expression pneumatic arranged in opposing relation to said regulating pneumatic, an actuating lever for said valve fulcrumed at one end to swing in the plane of movement of the movable boards of said pneumatics, said valve having a stem suspended from said lever intermediate its ends, a rock arm fulcrumed at the free end of the lever for movement crosswise thereof, links extending in opposite directions from the ends of the rock arm and connected, respectively, to the movable boards of said regulating pneumatic and said expression pneumatic, and pneumatically operated clutch means connected to the movable board of the expression pneumatic for holding the same in different intermediate positions.

8. An expression device for automatic musical instruments, comprising a regulating pneumatic, a regulating valve interposed between the source of power and the playing

action of the instrument, an expression pneumatic arranged in opposing relation to said regulating pneumatic, an actuating lever for said valve fulcrumed at one end to swing in the plane of movement of the movable boards of said pneumatics, said valve having a stem suspended from said lever intermediate its ends, a rock arm fulcrumed at the free end of the lever for movement crosswise thereof, links extending in opposite directions from the ends of the rock arm and connected, respectively, to the movable boards of said regulating pneumatic and said expression pneumatic, a plurality of auxiliary expression pneumatics, a rock shaft carrying arms operatively connected to said auxiliary pneumatics, a second arm carried by said shaft and connected to the valve-stem, a spring applied to the latter and interposed between said second arm and said actuating lever, said second arm controlling the regulating valve in response to the actuation of said auxiliary expression pneumatics and independently of the actuating lever, and pneumatically operated clutch means connected to the movable board of the expression pneumatic for holding the same in different intermediate positions.
